UNITED STATES PATENT OFFICE.

GEORGE A. BONELLI, OF KINGMAN, ARIZONA.

DRIVING MECHANISM FOR AUXILIARY SEATS FOR CHAIRS.

1,359,786.

Specification of Letters Patent. Patented Nov. 23, 1920.

Application filed September 20, 1919. Serial No. 325,145.

To all whom it may concern:

Be it known that I, GEORGE A. BONELLI, a citizen of the United States, residing at Kingman, in the county of Mohave and State of Arizona, have invented new and useful Improvements in Driving Mechanism for Auxiliary Seats for Chairs, of which the following is a specification.

This invention relates to a seat for an operator adapted to be moved about a chair in which a subject may sit. It is especially adaptable to barber chairs.

The objects of this invention are first, to provide a seat attached to a chair which may be moved to a position convenient for the operator to work upon the subject; second, to provide a seat of the character described which has means for propelling it so that it is not necessary for the operator to dismount from the seat in order to move the same; and third, to provide a seat of the character described with means within reach of the operator without dismounting from the seat, whereby he may control the turning of the chair, propelling of the seat, and various adjustments of the seat.

These objects will be more fully understood, as will also other objects and corresponding accomplishments of my invention from the following detailed description of a preferred embodiment thereof. For the purpose of this description, reference is had to the accompanying drawing, in which:

Figure 1 is a side elevation of a chair and seat constructed in accordance with my invention; Fig. 2 is a fragmentary detail in section as seen on the line 2—2 of Fig. 1, the yokes being omitted for clearness; Fig. 3 is a section taken on the line 3—3 of Fig. 2, part being shown in elevation and the yokes being omitted for clearness; Fig. 4 is a section taken on the line 4—4 of Fig. 1; and Fig. 5 is a section taken on the line 5—5 of Fig. 1.

Referring more particularly to Fig. 1, A indicates a chair of the type in common use in barber shops. Attached thereto is the seat for the barber or operator indicated generally by B.

The chair is supported upon a standard 6 which rests in a base 7. The chair may be revolved.

Journalized upon the base 7 are collars 8 and 9, which are attached to a carriage casing 10 in which is a driving wheel 11 resting upon the floor supporting the carriage,

and used to propel the same. By this construction the seat is pivoted to the chair and may revolve around it in a circle. A standard 12 for the seat proper extends from the top of the carriage 10 and is bent at 60 an angle. Mounted upon the horizontal part of the standard 12 is an adjustable head 14, whereby the seat may be moved to or from the chair and secured in position by any suitable means.

The collar 8 is attached to casing 10 by arms 15 and 16. A similar set of arms extend from collar 9 and are secured at their ends to carriage casing 10, one of the arms being indicated by 17 in Fig. 1. The arms 70 are suitably connected by braces forming a rigid frame.

Mounted in the frame is an electric motor 18 having a shaft connected by a universal joint 19 to a shaft 20. Shaft 20 carries adjacent its end a friction wheel 21. The shaft is journaled in the casing upon a pair of yokes 22 and 23 as shown in Fig. 4. The yokes have their openings crossing at right angles to one another, yoke 23 having a stem 80 24 guided in a bearing 25 so that it may slide therein and a stem 26 slidably guided in a bearing 27. Stem 26 is secured to a bell-crank 28, which is secured at its other end to a link 29. Link 29 may be moved 85 longitudinally by means of a lever 30 pivoted to the frame, a pedal bar 31 extending transverse thereof and provided at opposite ends with treads 32 and 33. Upon depressing tread 32, link 29 is moved outwardly 90 away from the chair and yoke 23 is forced downwardly, thereby moving the friction wheel 21 downwardly and to the left. Depression of tread 33 moves the link 29 in the opposite direction, and friction wheel 21 95 upwardly and to the right. Yoke 22 is similarly constructed and has a stem 34 connected by a bell-crank lever to a link 35 shown in Fig. 5. Link 35 is moved by a pedal bar 36 having treads 37 and 38. 100 Depression of tread 37 will move friction wheel 21 downwardly and to the right, while depression of tread 38 will move friction wheel 21 upwardly and to the left. In

order to avoid the motor being continuously 105 in operation, and only to operate it when one of the treads is depressed any convenient type of switch connected in the motor circuit may be operated by the pedal bars to throw the motor out of the circuit when 110 the pedal bars are in neutral position and

in circuit when any are moved from neutral position. This switch forms no part of my invention and is indicated conventionally by 39.

5 Within the carriage casing and in contact with the periphery of the propelling wheel 11 are friction wheels 40 and 41. These wheels are in the same plane as friction wheel 21, so that upon depression of the latter to the left motion will be transmitted to friction wheel 40 and upon depression of the friction wheel 21 to the right, motion will be transmitted to friction wheel 41. Thus, the propelling wheel may be operated in either direction by depression of the proper pedal. In this manner the seat may be propelled about the chair in either direction by the operator pressing the proper tread with his feet. It is desirable that a brake be applied to the propelling wheel when the latter is not being driven. For this purpose a brake shoe 42 is mounted upon a pivoted arm 43 operated upon by a spring 44', see Fig. 3. By this construction, the brake shoe is held against the propelling wheel, unless the free end of arm 43 is depressed. It is necessary to release the brake when the propelling wheel is operated, and as the latter is operated only upon depression of friction wheel 21, a bar 44 is secured thereto and engaged by depression of shaft 20.

The following means are provided for turning the chair. Mounted on the standard are crown gears 45 and 46 spaced apart with the teeth thereof facing each other. Disposed for engagement with the crown gears is a pinion 47 mounted upon a shaft 48 having a universal joint. Shaft 48 extends into the carriage casing and has fixed thereon a friction wheel 49 disposed to be engaged by the friction wheel 21 when the latter is raised to the left. A bell-crank lever 50 is connected to the shaft adjacent the pinion and operated by a link rod 51, which in turn is connected to a pedal bar 52 arranged to be moved in either direction. Pedal bar 52 has treads 53 and 54. By depressing tread 38, the friction wheel 21 is thrown into engagement with friction wheel 49, thereby operating shaft 48. To turn the chair in one

direction, tread 54 is then depressed placing pinion 47 in engagement with crown gear 45. To turn the chair in the opposite direction tread 53 is depressed thereby moving pinion 47 into engagement with crown gear 46 and turning the chair in the opposite direction.

The operator's seat may be raised and lowered by mechanical power. The standard bar 12 has a screw 55 formed thereon, as shown in Figs. 2 and 3. Screw 55 is in mesh with a pinion 56 mounted upon a shaft 57. Secured to shaft 57 is a friction wheel 58. Upon movement of the friction wheel 21 into engagement with friction wheel 58, the rack and seat will be raised therewith. This is accomplished by depressing tread 33. In order to maintain the seat in its upper position, a click and spring 59 is disposed to engage the screw 55. A dog 60 operated by a pedal is disposed in position below click 59. The click locks the post 12 in position and by depression of pedal 63 may be kicked out of engagement therewith so as to permit the seat to be lowered. The screw 55, click 59 and pinion 56 permit the seat to be turned around as desired.

For the convenience of the operator a standard 61 is secured to the chair and has adjustably secured thereto a table 62 for containing the operator's tools.

Although I have shown my invention as applied to a barber's chair, it is not limited to such use. The invention may be embodied in any chair wherein a subject sits, and an operator works upon the subject.

What I claim is:

In a driving mechanism, the combination of a drive shaft mounted so as to be swung in every direction transverse thereto, crossed yokes in which said shaft is journaled, means to independently move said yokes and thereby move said shaft transversely, a driving wheel on said shaft, driven wheels disposed to be engaged by said driving wheel upon movement of said yokes.

In witness that I claim the foregoing I have hereunto subscribed my name this 12th day of September, 1919.

GEORGE A. BONELLI.
